DOOR CONSTITUTING A REMOVABLE AND
CHANGEABLE REFRIGERATING UNIT FOR
REFRIGERATING PLANTS

Edison Calatroni, Paris, France

Application July 25, 1934, Serial No. 736,951
In France June 27, 1934

6 Claims. (Cl. 62—116)

My invention relates to refrigerating plants or machines and more particularly to refrigerator cabinets and the like and refrigerating means associated therewith.

5 Mechanical refrigerators and more particularly those of the household type generally comprise a suitable cabinet and freezing apparatus, the component parts of which are located, depending on their function, either inside or 10 outside said cabinet.

The main object of my invention relates to improvements in such refrigerators.

According to my invention, the complete refrigerating apparatus is very compact and is 15 located between the outside and inside walls of the door or a corresponding part of the cabinet, the various parts being conveniently connected together and placed on a common support, so as to permit easy removal and replacement of 20 any part for inspection and repairs and the transformation of suitable cabinets to mechanical refrigerators.

25 In the accompanying drawings which show a preferred embodiment of a door according to my invention which is designed for a refrigerating cabinet:

Fig. 1 is a front view of the door seen from inside the cabinet, the inside wall of the door being removed,

30 Fig. 2 is a vertical section along the line II—II of Fig. 1,

Fig. 3 is a vertical section along the line III—III of Fig. 1,

Fig. 4 is a horizontal section along the line 35 IV—IV of Fig. 1,

Fig. 5 is an axial section of a compressor shown in Figs. 1 to 4.

Fig. 6 is a section along the line VI of Fig. 5,

Fig. 7 is a front view of the cabinet provided 40 with the door according to my invention.

In the constructional form shown in the drawings, there is secured, on the inner side of door 1 of a domestic refrigerating cabinet by means of bolts 2, a frame 3 provided with a number of 45 seats 4, 5, 6 which are to receive the condensers 7, the compressor 8 and the evaporator 9 respectively. A convenient insulating wall 10 separates the evaporator 9 from other parts.

The compressor 8 comprises as more particu- 50 larly seen in Figs. 5 and 6 an electric motor, the rotor 11 of which is provided with a hollow shaft 12 constituting a pump cylinder which accommodates a piston 13 the end of which pro- 55 trudes out of cylinder 12 and is provided with a cam 14 the peripheral edge of which is ac-

commodated between abutments 15—16 located on rotor 11.

The piston 13 is provided on its rear part with pins 17 accommodated in corresponding recesses 18 of the frame 19 of the compressor which prevent said piston from rotating, and which at the same time, constitute an oil pump.

The piston 13 is hollow, its right hand end as shown in Fig. 5 freely enters into the chamber located inside frame 19 and its left hand end 10 is provided with a delivery valve 20. A delivery valve 21 is located at the corresponding end of cylinder 12 which opens into the duct 22 (Figs. 1 and 5) of evaporator 9.

As more particularly seen in Figs. 1 and 3, 15 evaporator 9 is provided with drawers 23—24 divided into compartments as usual for the formation of ice blocks, said drawers being completely within said evaporator.

Provided on the lower end of said evaporator 20 is a pipe 25 bringing said evaporator into communication with the coil 26 of condenser 7. Said pipe 25 has a conveniently determined and calibrated cross section for controlling the action of the compressor in drawing refrigerant from 25 the evaporator as determined at the time of constructing the apparatus.

As shown in the drawings, the unit comprising all refrigerating parts or elements secured on the door 1 is covered with a wall 27 30 conveniently provided with an insulating lining at its inner side. Said wall 27 thus forms together with the door itself a suitably insulated space which is divided in two compartments by means of the insulating partition 10 (Fig. 1). 35

The compartment 29 (Figs. 1 and 2) which accommodates the compressor 8 communicates with the external air through openings 30 provided in the door itself.

The second compartment 31 which contains 40 the conveniently insulated evaporator 9 is provided at its upper part with an air inlet 32 and at its lower part with an air outlet 33. Said openings are provided in the upper side 34 and 45 in the lower side 35 respectively of the part of the door which protrudes into the refrigerating chamber. Due to said openings and to the orientation of same an important circulation of the air contained in the refrigerating chamber takes 50 place round the evaporator 9 thus securing in an efficient manner the keeping of the atmosphere of said chamber at a low temperature, which results in efficiently keeping in good condition substances or foods located in said chamber. 55

Such a circulation of air is maintained without the aid of additional baffles.

For effecting a removal of the plant, it is sufficient to remove the bolts which constitute the pins of hinges 36 of door 1 then to withdraw said door together with the parts carried by same, and to substitute another door in condition for operation without causing a noticeable interruption in the operation of the refrigerating cabinet. The removed door may afterwards be carried to a shop where the several parts can be conveniently inspected and repaired. The soldered or welded parts may thus be easily separated and soldered again with a safety which is not easily attained when the refrigerating plant has to be repaired on the spot. It would also be possible in some cases to leave the door in position, the frame 3 with the parts supported by same only being removed by loosening the bolts 2, and substituted by another frame with its parts.

It would of course be possible to obtain reciprocation of piston 13 by providing in the piston 13 a suitably designed groove, and to provide rollers entering said groove, said rollers being journalled on the rotor 11.

It would also be possible in some cases, to use as a piston, the core of a solenoid or of an electro magnet.

30 It is to be noticed that thanks to the described arrangement, the safety of operation is greatly increased for the reason that all connections are made in the work shop and have not at all to be undone after the putting in operation of the apparatus. Said connections may thus be made by soldering or even by welding, thus eliminating any danger of leakage. Also, due to the fact that the compressor does not necessitate any packing any tendency to leak is minimized.

40 What I claim is:

1. The combination of a removable and interchangeable refrigerator-cabinet door having an outside wall and an inside wall, and a complete refrigerating and cooling plant carried by the door between said walls, said plant being of requisite capacity for food preservation in a corresponding cabinet.

45 2. The combination of a removable and interchangeable, relatively thin refrigerator-cabinet door having an outer wall and an inner wall, a complete refrigerating and cooling plant with

all of its parts arranged between said walls, and a support for all of said parts detachably carried by said door between said walls, whereby they can readily be inserted in the door and removed therefrom, said plant being of 5 adequate capacity to preserve food in a corresponding cabinet.

3. In a refrigerator including a cabinet, a removable and interchangeable door having an outer wall and an inner wall, a complete refrigerating and cooling plant between said walls, such plant being of adequate capacity for the cabinet and including an evaporator, a heat-insulation partition shutting off a compartment including said evaporator, outlet means for the 10 passage of cold air from the evaporator compartment to the interior of the cabinet, and inlet means for the passage of air from the interior of said cabinet into the evaporator compartment.

4. In a refrigerator including a cabinet, a removable and interchangeable door for said cabinet having an outer wall and an inner wall, a complete refrigerating and cooling plant being of adequate capacity for the cabinet and between said walls, such plant including a compressor, a 25 condenser and an evaporator, heat-insulation means setting off a compartment containing said compressor and condenser and excluding said evaporator, and inlet and outlet means for the admission of outside air into said compartment 30 and the discharge of air from said compartment into the outside air.

5. In a refrigerator including a cabinet, a removable and interchangeable door for said cabinet having an outer wall and an inner wall, a 35 complete refrigerating and ice making plant between said walls, such plant including an evaporator, heat insulation means setting off a compartment containing said evaporator, and a 40 freezing compartment projecting into the evaporator compartment and adapted to receive ice containers.

6. In a refrigerator including a cabinet having an opening therein, a generally flat closure for 45 said opening, said closure having an outer and an inner wall, and a complete refrigerating and cooling plant supported by said closure between said walls; said plant being of adequate capacity for said cabinet.

EDISON CALATRONI.
